UNITED STATES PATENT OFFICE

2,490,380

FOLDABLE CRUTCH

Oliver T. Schweppenheiser, Philadelphia, Pa.

Application May 9, 1946, Serial No. 668,582

1 Claim. (Cl. 135—49)

1

Crutches, as ordinarily constructed, are clumsy and awkward to handle when a person is getting into and out of a chair and many different types of vehicles, such as, for example trolley cars, busses, carriages and automobiles.

The object of this invention is to devise a novel construction and arrangement of a crutch which can be folded when not in use to take up but a minimum of space, and, which, when extended can be securely locked to prevent relative movement of the foldable parts.

The crutch is preferably fabricated from light weight tubular material, such as aluminum or magnesium, and has provisions for varying its over-all length to adapt it for use by persons by different heights.

With the foregoing and other objects in view as will hereinafter clearly appear, my invention comprehends a novel crutch.

It further comprehends a novel crutch comprising two main parts pivoted together to provide for their folding into a compact size which can be easily carried, and novel locking mechanism for locking the parts in their extended condition ready for use.

For the purpose of illustrating the invention, I have shown in the accompanying drawings a preferred embodiment of it which I have found, in practice, to give satisfactory and reliable results. It is, however, to be understood that the various instrumentalities of which the invention consists can be variously arranged and organized and the invention is not limited to the exact arrangement and organization of these instrumentalities as herein set forth.

Figure 1 is a perspective view of a crutch embodying my invention.

Figure 2 is a side elevation, partly broken away for clearness of illustration.

Figure 3 is a side elevation, showing the crutch in folded condition.

Figure 4 is a section on line 4—4 of Figure 2 and showing more particularly the locking mechanism.

Figure 5 is a sectional detail, showing a different type of ground engaging member.

Similar numerals of reference indicate corresponding parts.

Referring to the drawings:

The crutch has upper, tubular, side members 1 and 2, connected at their upper ends by a cross bar 3 having its top face concave to fit under the armpit of the user. The cross bar 3 has depending lugs 4 which have a close fit in the side

2

members and are fixed thereto in any desired manner, for example by pins 5. A spacing bar 6, forming a hand grip, is secured to the side members by fastening devices 7.

5 The crutch has lower, tubular, side members 8 and 9, which converge forwardly and are connected at their forward ends to a block of material 10 having any desired contour. This block 10 is provided with lugs 11 fixed in the side members 8 and 9 by fastening devices 12. The block 10 is apertured to receive a tube 13 fixed to it by set screw 14. The tube 13 has a conventional ground engaging member 15 of cushioning material.

15 The upper ends of the members 8 and 9 are closed by lugs 16 depending from an U-shaped channel 17 in which L-shaped locking plungers 18 and 19 are slidable. A spring 20 between the plungers tends to move the plungers outwardly 20 into their locked position. A side of the channel 17 is cut out as at 21 and 22 to provide clearance for the grasping portion of the plungers. The top of the channel 17 is closed by a cover 23 detachably secured to it by fastening devices 24.

25 The lower ends of the side members 1 and 2 are closed by fillers 25 having slots 26 to receive the locking plungers 18 and 19 and apertured to receive a pivot 27 which passes through the side members 8 and 9 and the lugs 16. The ends of the pivot are threaded to receive cap nuts 28.

If the crutch is to be used on ice, a tip 30 having a pointed end is substituted for the member 15 and has its shank screwed into a sleeve 31 in the forward end of the tube 13.

35 It will now be apparent that when the crutch is folded, the lower members 8 and 9 fold within the upper members 1 and 2 to form a flat package as shown in Figure 3, and form a very compact article for carrying or for shipping. When the parts are unfolded, the locking plungers 18 and 19 are pressed toward each other so that when in alignment with the slots 26 and released they will enter such slots to securely lock the upper and lower section of the crutch in their extended position.

The tube 13 can be adjusted in the block 10 to provide a crutch having a desired over-all length to suit the individual user.

40 Having thus described my invention, what I claim as new and desire to secure by Letters Patent is:

In a crutch, an upper section having tubular side bars, a lower section having tubular side bars, fillers closing the lower ends of the side

bars of the upper section and having with the upper side bars plunger receiving slots and pivot openings, a cross member extending across the upper ends of the lower side bars and having fillers extending into the upper ends of the side bars of the lower section, a pivot member in the pivot openings and passing through the upper and lower bars and their fillers, locking plungers carried by said cross member to enter the slots in the upper side bars and their fillers, a spring 10 tending to move the plungers into their slots, and a ground engaging member carried by said lower section.

OLIVER T. SCHWEPPENHEISER.
